Patented Nov. 26, 1918.

INVENTOR.
Frank J. Stumpf,
Charter-Searge, *his ATTORNEY.*

UNITED STATES PATENT OFFICE.

FRANK J. STUMPF, OF KANSAS CITY, MISSOURI, ASSIGNOR OF ONE-HALF TO RICHARD T. CONNELL, OF KANSAS CITY, MISSOURI.

WELL-PACKING CONSTRUCTION.

1,286,141.

Specification of Letters Patent. Patented Nov. 26, 1918.

Application filed February 26, 1918. Serial No. 219,299.

To all whom it may concern:

Be it known that I, FRANK J. STUMPF, a citizen of the United States, residing at Kansas City, in the county of Jackson, State 5 of Missouri, having invented certain new and useful Improvements in Well-Packing Construction, of which the following is a full and exact specification.

This invention relates generally to well 10 cleaning apparatus, and one of the objects of the invention is to provide an improved means for packing the space between the pump tubing and the sides of the well or well lining above the steam jet outlets.

15 It is a further object to provide in this connection a packing construction having means whereby the packing is automatically expanded into engagement with the sides of the well or well lining as the pump tubing reaches the vicinity of the bottom of the 20 well.

It is also sought to devise a simple and efficient construction of the character described, and of a type which will be economical 25 in its operation and inexpensive in the necessary details for applying the same to the pumping apparatus.

With these general objects in view, the invention will now be described with reference 30 to the accompanying drawing illustrating one form of construction and arrangement for embodying the improvements in a well pumping apparatus, after which the features of novelty therein will be set forth and defined in the appended claims.

In the drawing—

Figure 1 is a vertical sectional view of a well 40 cleaning apparatus constructed in accordance with the present invention, being a section taken along the line 1—1 of Fig. 2;

Fig. 2 is a vertical sectional view of the well lining and showing the well cleaner construction in elevation; and

Figs. 3 and 4 are transverse sections taken 45 on the lines 3—3 and 4—4, respectively, of Fig. 1.

Referring to the drawing in detail, this shows a sectional casing 6 forming the liner of a well, such as is commonly used in oil 50 wells for which the present improvements are particularly designed, the sections of which casing are connected together by means of couplings 8, and the lowermost section is formed with the usual series of 55 strainer openings 10. Inside the casing 6 is

provided the usual string of pump tubing 12 having the strainer perforations 14 in its lower end portion, and inside this tubing 12 is positioned a steam line 16 having its lower end fitted with a nozzle attachment 18, which 60 is secured in place by means of a coupling 20, said nozzle extending below the end of the tubing 12, when the latter is in position, for the purpose of ejecting the steam all around the bottom of the well below the tubing. The lower end portion of the steam line 16 is further provided with a series of radial jet tubes 22 extending out through the tubing 12 and having flattened nozzle tips communicating with the exterior face of said 70 tubing as shown in Figs. 1 and 2.

Packing means is provided for sealing the space between the casing 6 and pump tubing 12 above the steam jets, and this means comprises two packing members carried in 75 different longitudinal positions by the pump tubing and having the following construction. A fixed collar 24 is secured to the exterior face of the pump tubing 12, and this collar serves to secure the upper ends of a 80 series of spring elements 26, the lower ends of which are secured to a collar 28 mounted slidably on the outer face of the tubing 12. To the collar 28 are also secured the upper ends of a series of spring elements 30 having 85 their lower ends secured to a second sliding collar 32. Relative approaching movement of the several collars 24, 28 and 32 will obviously effect outward movement of said spring elements 26 and 30 away from the 90 tubing 12 into bowed position, as illustrated in Figs. 1 and 3, whereby a flexible sleeve covering 34, surrounding said spring elements and tightly secured to said collars by means of clamping bands 36, is expanded 95 into engagement with the interior of the casing 6. The sleeve 34 is of any suitable flexible material adapted to pack the space between the tubing and casing, such as a rubber-treated canvas which will not be 100 readily affected by the materials with which it comes in contact when used in this relation.

Means is also provided for automatically expanding said packing means on lowering of the pump tubing into the position shown 105 in the drawing. This means comprises a series of rods 38 connected to the lower sliding collar 32 and having the lower ends of said rods secured to a foot-piece 40 at a slight distance below the nozzle attachment 110

18. The arrangement is such that so long as the foot-piece 40 is suspended free of engagement with the bottom of the well, its weight, together with that of the sliding collars, will hold the packing members collapsed or contracted substantially flat against the sides of the pump tubing; but when lowered into the position shown by the drawing, with the foot-piece stopped against 10 further movement by the bottom of the well, the slight further movement of the pump tubing after the foot-piece has come to rest effects relative approaching movement of the collars 24, 28 and 32—as will be obvious, 15 thereby causing the outward bowing of the spring elements 26 and 30, and the consequent expanding of the packing sleeve 34, and thus tightly packing the space above the steam jets.

20. In the cleaning operation, after the packing construction has been actuated in the manner described, steam is forced under high pressure down through the steam line 16 and the steam issues in forcible jets 25 through the nozzle 18 and jet tubes 22; the action of the steam soon boils all the contents of the bottom of the well and at the same time produces a violent turbulent motion or agitation of said contents, so that the 30 caked deposits are loosened up and the openings or perforations 10 and 14 freed of all obstructions. The space between the pump tubing and the casing 6 being sealed by the packing members, the oil and the material 35 carried along with it are driven under the force of the steam up through the pump tubing 12 and may be carried off by an outlet pipe 42 into any suitable receptacle (not shown). The object of having a series of 40 packing members is to insure greater effectiveness as well as certainty in the packing operation; if one of the packing members should come opposite a defective or gaping joint in the casing 6, or if there should occur 45 an unevenness in the casing or if the casing should be split or otherwise defective at a certain point, so that this packing member would not function properly, the other packing member may nevertheless be depended 50 upon to provide an effective seal between the casing and pump tubing.

It will thus be apparent that a simple, compact and efficient arrangement and construction have been devised for carrying out

the desired objects of the invention, and 55 while I have shown and described what is now regarded as the preferred form of construction, the right is reserved to such formal changes or modifications as may fairly fall within the scope of the following claims. 60

What I claim is:

1. Well packing apparatus comprising, in combination with the pump tubing, packing means comprising a fixed collar carried by said tubing, a sliding collar mounted on said tubing below said fixed collar and connected with the latter by a series of spring elements adapted, on relative approaching movement of said collars, to bow outwardly away from said tubing, a flexible packing element surrounding said spring elements, and means connected with said sliding collar and actuated by engagement with the bottom of the well, on lowering of said tubing, to expand said packing means. 75

2. Well packing apparatus comprising, in combination with the pump tubing, packing means comprising a series of expansible packing members carried by said tubing and connected together in different longitudinal 80 positions along said tubing, and means connecting with the lower of said packing members and actuated by the lowering of said tubing to simultaneously expand said packing members, said lower packing member 85 serving to transmit the action of said expanding means to the next upper packing member connected thereto.

3. Well packing apparatus comprising, in combination with the pump tubing, packing means comprising a fixed collar carried by said tubing, a pair of collars slidably mounted on said tubing below said fixed collar and connected to each other and to said fixed collar by a series of spring elements 90 adapted, on relative approaching movement of said collars, to bow outwardly away from said tubing, a flexible packing element connected to said collars and surrounding said spring elements, and means connected with the lower of said sliding collars and actuated by engagement with the bottom of the well, on lowering of said tubing, to expand said packing means. 95

In witness whereof I have hereto affixed 105 my signature.

FRANK J. STUMPF.
